* cited by examiner

Primary Examiner — Omeed Agilee(74) *Attorney, Agent, or Firm* — Sterne, Kessler, Goldstein & Fox P.L.L.C.; Charles B. Cappellari(57) **CLAIM**

The ornamental design for a cover for a tray, as shown and described.

DESCRIPTION

FIG. 1 is a top perspective view of a cover for a tray showing the claimed design; and,

FIG. 2 is a bottom perspective view thereof.

The broken lines in the figures show portions of the cover for a tray that form no part of the claimed design.
